VACUUM CLEANER

Gustaf Einar Lofgren, Riverside, Conn., assignor
to Electrolux Corporation, Dover, Del., a corporation of Delaware

Application January 31, 1941, Serial No. 376,760

2 Claims. (Cl. 220—55)

My invention relates to vacuum cleaners and more especially to those of the inclosed bag type. Still more particularly, it relates to an improved means for removably securing a closure member to the casing of such a vacuum cleaner.

Further objects and advantages of my invention will be apparent from the following description considered in connection with the accompanying drawings, which form a part of this specification and of which:

Fig. 1 is a side view, partially in cross section, of a vacuum cleaner embodying my invention.

Fig. 2 is an end view, looking from the left of the vacuum cleaner shown in Fig. 1.

Fig. 3 is a cross-sectional view on an enlarged scale taken on the line 3—3 of Fig. 2.

Fig. 4 is a cross-sectional view on an enlarged scale taken on the line 4—4 of Fig. 1; and

Fig. 5 is a view, partially broken away, of the inner side of a closure member illustrated in the other figures.

Referring to the drawings, reference character 10 designates the casing of a vacuum cleaner. This casing is preferably made of sheet metal and has a substantially cylindrical form. Supported within the vacuum cleaner in any suitable manner is a motor-fan unit including an electric motor 11 and a centrifugal fan 12. The casing is adapted to be supported horizontally on a horizontal surface by means of runners 13 which are secured thereto by brackets or the like 14. An end cap 15 is secured to the casing 10 and is provided with an exhaust opening 16. A carrying handle 17 is secured to the upper part of the casing near the rear end thereof so that the center of the handle is approximately over the center of gravity of the unit. A generally U-shaped channel member 18 is likewise secured to the upper part of the casing 10 and extends from the forward end of the handle to the front end of the casing.

Secured within the casing adjacent to its front end is a circular channel 19 which is L-shaped in cross section. A ring 20 is secured to the channel 19 and is formed with an inturned flange 21 which extends within the channel. The outer periphery of the ring 20 is formed with a U-shaped cross section, as is shown at 22, so as to embrace the end of the cylindrical casing 10. The ring 20 provides a seat for a dust bag ring 23 which has a radially extending flange 24 provided with a gasket 25 which is adapted to be clamped between the ring 20 and a seat 26 formed by a substantially circular plate 27 which constitutes a portion of a removable closure member, designated gen-

erally by reference character 28. The open mouth of a dust bag 66 is secured to ring 23 and occupies the space within the casing between the front end of the latter and the motor-fan unit.

Also constituting a portion of the closure member 28 is a dish-shaped member 29, the rim of which is secured in any suitable manner to the edge of plate 27. Plate 27 and member 29 are formed with aligned openings between which extends a hollow member 30, preferably of Bakelite or similar material. Member 30 is formed with a plurality of lugs 31 which are engaged by an inturned lip 32 on the member 29, while a gasket 33 may be interposed between the inner end of member 30 and the plate 27 in order to provide an airtight seal. As shown, the member 29 and plate 27 are secured together with the member 30 and gasket 33 clamped therebetween by means of bolts 34. If desired, a metallic liner 35 may be placed within member 30 and formed with an inturned flange 36. A hose or the like 37 may be connected to this inlet opening by means of a coupling member 38, known per se, provided with spring-pressed latches which engage the flange 36.

Secured to the outside of the member 29 at the center of the upper portion thereof is a hook-like member 40. This member is covered and substantially concealed from view by means of a channel 41 which may be fastened to the member

29 in any suitable manner, as by means of ears 39 which extend through openings formed in member 29. The contour and location of channel 41 is such that, when the closure member 28 is in place, this channel forms a continuation of the

35 channel member 18 on the casing 10. Secured to the casing 10 underneath the channel member 18 is a hook-like member 42 which is adapted to be engaged by the member 40 so as to properly locate the closure member and to support it loosely in place. Channel member 18 is formed with a recess, as is indicated at 43, whereby the hooked end of member 42 is exposed for engagement by the hooked end of member 40.

Secured to the outside of a dish-shaped member 29 at diametrically opposed points, each of which is approximately 90° from member 40, are resilient members 44. One of these members is shown in Fig. 4 and a similar member is secured to the opposite side of member 29. As shown,

50 members 44 are secured in place by means of rivets. Members 44 are substantially concealed from view by means of a channel 45 secured to the front of member 29 by means of ears 46 extending through apertures 47. As shown particularly in Fig. 2, channel 45 extends all the way across the

front of the closure member and is provided with circular recess 48 to accommodate the upper portion of member 30. The ends of the web of channel 45 are recessed, as is shown at 49, in order to expose the hooked end of each member 44, and the web extends inwardly, as shown at 65 so as to contact or be close to member 44.

Opposite sides of casing 10 adjacent to channel 18 are formed with depressions 50, in each of which is secured a bracket 51 as by rivets 52. The end of bracket 51 which is adjacent to the end of the casing is formed with an apertured lug 53 which carries a pin 54. Pivoted on this pin is a lever 55 in the form of a U channel, the web portion of which is partially cut away, as is indicated at 56. Pivoted secured to the flanges of lever 55 by means of a pin 57 is a latch member 58 which has a hooked end 59 adapted to engage the hook-shaped resilient member 44.

Channel members 60 are secured on the sides of casing 10 in alignment with the channel 45 on the closure 28 so as to form a continuation thereof when the closure member is in place. Channel 60 may be secured in place by means of bolts 61 which extend through channel 19 to engage a nut or the like 62. The head of bolt 61 is concealed from view by means of latch 58 when the parts are in assembled position. Channel 60 is recessed at 63 in order to accommodate lever 55 and latch 58 and ample space is provided at the right-hand end of the recess for insertion of the finger underneath the web portion of lever 55. Chiefly for the sake of appearance, a shallow dish-like member 64 may be secured in the bottom of depression 50.

It is believed that the operation of the above-described device will be largely apparent. If it is desired to remove the closure member 28, the parts being in the position shown in the figures, the operator places a finger under the end of each of the levers 55 and pivots them outwardly from the casing. This causes the pins 57 to swing in arcs around the respective pins 54 and thus to move the hooked ends 59 of the latches 58 to the left, as viewed in Fig. 4. This in turn releases them from the resilient members 44 and the portions 65 of the channel 45 assures that the latches move completely out of engagement with the members 44. When the closure member is so released, it does not fall away from the casing, but remains suspended by virtue of the engagement of the hook members 40 and 42. However, it may be easily removed by lifting it and at the same time moving it slightly to the left, as viewed in the figures.

When the closure member has been removed, the bag 66 may be taken out for the purpose of emptying it, and then replaced. The closure member is then placed with the member 40 engaging member 42. The closure member 28 is suspended thereby in position with the resilient members 44 in alignment with the corresponding latches 58 and levers 55. This relieves the hands from supporting the closure member 28 and frees them to engage levers 55. The levers 55 are pivoted toward the cleaner casing. At the same time, the latch members 58 are pressed inwardly so that the hooks 59 thereon will engage the resilient members 44. The arrangement of the parts is such that, when the parts are in the position illustrated in Fig. 4, latch member 58 has been drawn to the right, as viewed in this figure, sufficiently so as to distort somewhat the member 44, which is hence placed under ten-

sion. Consequently, the closure member 28 is tightly held against the gasket 25 of the dust bag ring. As will be observed, the axis of pin 57 is closer to the cleaner casing than is the axis of pin 54. Consequently, the force imposed on the latch member 58 by the distorted resilient member 44 tends to pivot the lever 55 in a counter-clockwise direction about the pivot 54. However, the member cannot pivot in this direction, inasmuch as it contacts member 64, and consequently this force has no tendency to pivot the lever in a clockwise direction to release the latch 58. In other words, if a straight line is drawn from the point of contact between the hooked end 59 with the resilient member 44 and the axis of pin 57, such line will pass between the axis of pin 54 and the casing of the cleaner.

While I have shown and described one more or less specific embodiment of my invention, it is to be understood that this has been done for purposes of illustration only and the scope of my invention is not to be limited thereby, but is to be determined from the appended claims.

What I claim is:

1. In a vacuum cleaner, a hollow casing having an opening, a removable closure member for said opening, a lever on either side of said casing, each lever having one end pivotally connected to said casing adjacent to said opening, a latch member pivoted on each lever at a point spaced from said end, a resilient member secured to either side of said closure member, means for securing one end of each resilient member to said closure member, the other end of each resilient member being hook-shaped, each resilient member being so formed that its central portion is bowed away from the closure member and the hook-shaped end thereof is urged into slidable contact with said closure member, said hook-shaped member being engageable by the respective latch members to secure said closure member in place, and a channel extending across the front of said closure member and substantially covering said resilient members, said channel being disposed close to said resilient members adjacent to the points of contact of said resilient members with said closure member.

2. In a vacuum cleaner, a hollow casing having an opening, a removable closure member for said opening, a lever on either side of said casing, each lever having one end pivotally connected to said casing adjacent to said opening, a latch member pivoted on each lever at a point spaced from said end, a resilient member on either side of said closure member, means for securing one end of each resilient member to said closure member, the other end of each resilient member being hook-shaped, each resilient member being so formed that its central portion is bowed away from the closure member and the hook-shaped end thereof is urged into slidable contact with said closure member, said hook-shaped ends being engageable by the respective latch members to secure said closure member in place, and a channel extending across the front of said closure member and substantially covering said resilient members, the web of said channel being cut away at the ends thereof to expose the ends of said resilient members, portions of the web extending inwardly so as to be close to said resilient members adjacent to the points of contact of said resilient members with said closure member.

GUSTAF EINAR LOFGREN.
